UNITED STATES PATENT OFFICE

143,111

DESIGN FOR A CONCRETE FENCE PANEL

William Ashenfelter, Swanton, Ohio

Application August 10, 1945, Serial No. 121,365

Term of patent 14 years

(Cl. D28—1)

To all whom it may concern:

Be it known that I, William Ashenfelter, a citizen of the United States and resident of Swanton, in the county of Fulton and State of Ohio, have invented a new, original, and ornamental Design for a Concrete Fence Panel, of which the following is a specification, reference being had to the accompanying drawing, forming a part thereof.

In the drawing, Fig. 1 is a front elevation of a concrete fence panel showing my new design, and Fig. 2 is an end view thereof.

Both sides of the panel are substantially the same in appearance.

I claim:

The ornamental design for a concrete fence panel, substantially as shown and described.

WILLIAM ASHENFELTER.
